RESISTOR TYPE FLAME DETECTOR

Justin A. Deubel, Hales Corners, Wis., assignor
to Perflex Corporation, Milwaukee, Wis., a corporation of Wisconsin

Application November 4, 1948, Serial No. 58,255

7 Claims. (Cl. 201—63)

1

This invention relates generally to thermal devices which respond to the presence or absence of flame and more particularly to a thermal device which responds immediately to the establishment of combustion in a heating plant and responds immediately to the cessation of combustion therein.

In control systems for fuel fed heating plants it is customary to provide a flame failure safeguard in the system to shut down the heating plant in the event that combustion fails either at the beginning of or at any time during a normal operating cycle of the heating plant. Such flame failure safeguards usually comprise a switch which is operated by the initial movement of a temperature responsive element to the initiation or cessation of combustion. Since initial movement of the temperature responsive element operates the switch, provision must be made for permitting the element to continue to move after switch actuation in response to additional heating of the element and yet de-actuate the switch immediately upon a reversal in direction of movement of the element. This is customarily accomplished by use of a "slip friction" device wherein some portion of the mechanism is permitted to slip against a frictional force upon continued movement of the element in the same direction after switch actuation.

The principal object of this invention is to provide an apparatus which, when wired into a suitable circuit, accomplishes electrically a flame detection function similar to that heretofore achieved by mechanical "slip friction" flame detectors.

A further object of this invention is to provide a flame detector which accurately and rapidly responds to the presence or absence of flame by creating a temperature differential between two temperature responsive resistances when a flame is present and rapidly decreasing this temperature differential when the flame is extinguished.

A further object of this invention is to provide a flame detector apparatus which because of its small size is easily and conveniently mounted within the influence of the flame in the combustion chamber of a heating plant.

Other objects and attendant advantages will be appreciated by those skilled in this art as the invention becomes better understood by reference to the following description when considered in connection with the accompanying drawings, in which:

Fig. 1 represents a side view of an embodiment of invention, a portion of a side wall broken away to show location of interior parts.

Fig. 2 represents a top sectional view of the device shown in Fig. 1, the section being taken generally along the line II—II of Fig. 1.

Fig. 3 is an end view of the device shown in Fig. 1.

Fig. 4 is a diagrammatic showing of a circuit,

2

and switch controlled thereby, utilizing the device illustrated in Figs. 1, 2 and 3.

Fig. 5 is a side view, partly in section of a portion of an oil burner illustrating the position at which the embodiment of the present invention may be mounted.

Referring now to Figs. 1, 2 and 3 the flame detector 10 comprises a tube rectangular in cross-section formed by channel-shaped member 11

10 and a base-plate 12 which may be of brass or other metal having a good thermal conductivity. The forward end 13 of tube 10 is open, the other end 15 is closed by means of a block 16 formed of Bakelite or other insulating material.

15 A strip 17 formed of a metal such as stainless steel is secured at one of its ends to the base-plate 12 in good heat conducting relation therewith by any suitable means such as rivets 18. A copper block 19 is secured to the free end of strip 17 by soldering or any other suitable means which provides for good thermal conductivity between strip 17 and block 19.

A first temperature responsive resistance 21 is mounted on an intermediate portion of strip 17

25 and a second temperature resistance 22 is imbedded in block 19. These resistances are of a type having a relatively high thermal coefficient of resistance. As illustrated, resistances 21 and 22 are of the thermistor type and have a high, negative thermal coefficient of resistance, that is, their resistance decreases at a rapid rate as their temperature increases as is well known in the art. Thermistor resistances 21 and 22 may be of any suitable outer configuration: as illustrated, they are of the bead type. It will be understood that resistances 21 and 22 may be of a type having a positive thermal coefficient of resistance, such as wire wound resistances, the principal requirement which they must fulfill in

35 regard to the present invention being that their resistance either increase or decrease rapidly with a temperature change.

30 Blades 23, 24, 25 and 26 extend through the Bakelite block 16 and leads 27 and 28 connect resistance 22 with blades 23 and 24 and leads 29 and 30 connect resistance 21 with blades 25 and 26. Blades 23, 24, 25 and 26 are connected with a conduit 32 which serves as a connecting lead between the flame detector and the heating plant controlling circuit, as will subsequently be explained.

40 It will be understood that the circuit shown in Fig. 4 and its operation form no part of the present invention. Other circuits might be devised utilizing the temperature responsive resistances 21 and 22, that shown being merely illustrative.

Fig. 4 illustrates a portion of a circuit utilizing the flame detector previously described. Transformer 33 has secondaries 34 and 35 which serve as a power source for energization of the circuit shown. Secondary 34 is connected across a resistance network 37 which comprises temperature

responsive resistances 21 and 22 and potentiometer 38. Secondary 35 furnishes the plate voltage for a gas filled electric discharge tube 39. Relay 36 is connected in the plate circuit of tube 39. The junction of resistances 21 and 22 is connected to the control electrode 31 of tube 39 through a network comprising resistance 40 and capacitor 41. Relay 36 serves to close switch 42 when energized. Switch 42 may be utilized in any suitable way to perform a control function in the heating plant controlling circuit, as well known in the art.

The circuit shown in Fig. 4 operates generally in the following manner: as long as resistances 21 and 22 are at the same temperature, the voltage output of network 37 is such as to hold the control electrode 31 of tube 39 at a potential below the cut-off potential of tube 39. If a temperature differential exists between resistances 21 and 22, their resistances become unequal and the voltage output of network 37 is increased sufficiently to raise the potential of the control grid 31 to allow the tube 39 to conduct, energizing relay 36 and closing switch 42.

Fig. 5 shows the nozzle portion of a gun type oil burner which is illustrative of the type of apparatus with which the present invention may be used. A blast tube 45 serves as a passage for delivery of air for the combustion of oil particles delivered from nozzle 46 under pressure, the oil being supplied through a central oil delivery pipe 48. Flame detector 10 is mounted in good heat conducting relation with a brass block 50 which in turn is held in good heat conducting relation with the pipe 48. Flame detector 10 and block 50 are held in place on pipe 48 by any suitable means such as metallic straps 51. Block 50 serves only to space flame detector 10 from pipe 48 sufficiently to clear the obstruction to radiant heat from the burning oil offered by nozzle 46. Depending upon the dimensions of nozzle 46, block 50 may be omitted from the mounting arrangement.

With the flame detector mounted as shown in Fig. 5 and with resistances 21 and 22 connected in the circuit illustrated in Fig. 4 the operation is as follows: while the heating plant is shut down, resistors 21 and 22 are at the same temperature, and their resistances are substantially equal. Under these conditions, the voltage output of network 37 is insufficient to raise the voltage of electrode 31 to cause tube 39 to conduct, and relay 36 remains deenergized. When the heating plant is placed in operation, the oil delivered at nozzle 46 is ignited and a flame is maintained adjacent the end of blast tube 45. Radiant heat from the flame strikes resistor 21 and a portion of strip 17 directly, and rapidly heats resistor 21 to a temperature well above the temperature of resistor 22 which is shielded from direct heat radiation. This temperature differential between resistor 21 and 22 causes their resistances to become unequal, increasing the voltage of electrode 31 (Fig. 4) to cause tube 39 to conduct and the relay 36 to be energized thereby closing switch 42. As additional radiant heat is absorbed by strip 17, the temperature of resistor 22 is also raised through heat conduction along strip 17, but since strip 17 has a good thermal connection with the relatively cool oil pipe 48 through block 50 some of the heat absorbed by strip 17 is lost by conduction to the pipe 48, and, additionally, heat is radiated from copper block 19. This serves to hold the temperature of resistor 22 slightly below the temperature of resistor 21 during operation of the heating plant and thereby, through a circuit such as

that shown in Fig. 4, holds switch 42 closed as long as a flame is present.

Should the flame be extinguished for any reason, the temperature of resistor 21 will immediately decrease since direct heat radiation from the flame will be cut off and strip 17 will lose heat by conduction through block 50 relatively rapidly. Because of the large mass to surface area ratio of block 19, however, the temperature of block 19 and consequently of resistor 22 will decrease relatively slowly. As a result the temperatures of resistors 21 and 22 will rapidly approach the same value and the temperature differential between resistors 21 and 22 will disappear.

This will result in the de-energization of relay 36 and opening of switch 42 relatively quickly after disappearance of the flame at the burner.

It will be noted that when coupled with a suitable circuit, such as that illustrated in Fig. 4, the flame detector embodying the present invention responds relatively rapidly to the initial appearance of a flame, is unaffected by continuing increase in temperature of the flame detector while a flame is present, and responds relatively rapidly to the disappearance of the flame and the consequent decrease in temperature of the flame detector.

Various modifications coming within the spirit of the invention may suggest themselves to those skilled in the art and hence the invention is not to be limited to the specific form shown, except to the extent indicated in the appended claims.

I claim:

1. An apparatus for detecting the presence or absence of flame in a combustion chamber comprising: a casing having an open end and adapted to be mounted so that said open end faces said flame, a member having high thermal conductivity within said casing and secured in heat conducting relation thereto in proximity to said open end, a first temperature responsive resistance mounted on said member in heat conducting relation therewith for exposure to direct heat radiation from said flame through said open end of said casing, said first resistance being heated to a first temperature when flame is present in said combustion chamber, a body having a relatively large mass to surface area ratio and high thermal conductivity secured to said member and shielded from direct heat radiation from said flame by said member, a second temperature responsive resistance mounted on said body in heat conducting relation therewith and adapted while flame is present in said burner to be maintained at a second temperature defining a temperature differential between said first and second temperatures; said casing, said member and said body forming a heat conducting path operating to rapidly decrease said temperature differential when said flame is extinguished.

2. An apparatus for detecting the presence or absence of flame in a combustion chamber comprising: a casing mounted in relation to said combustion chamber at a point the ambient temperature of which is below the temperature within said combustion chamber when flame is present therein, a first temperature responsive resistance mounted within an open end of said casing for exposure to direct heat radiation from said flame and heated to a first temperature when flame is present in said combustion chamber, a second temperature responsive resistance mounted within said casing in a position shielded from direct heat radiation from said flame, a

body having a relatively large mass to surface area ratio and high thermal conductivity associated with said second temperature responsive resistance for maintaining a temperature differential between said first and second resistances while flame is present in said combustion chamber, said casing and said body operating to rapidly decrease said temperature differential upon extinction of said flame.

3. An apparatus for detecting the presence or absence of flame in a combustion chamber comprising: a casing adapted to be mounted in relation to said combustion chamber at a point the ambient temperature of which is below the temperature within said combustion chamber when flame is present therein, a first temperature responsive resistance mounted within an open end of said casing for exposure to direct heat radiation from said flame and heated to a first temperature when flame is present in said combustion chamber, a member having high thermal conductivity secured in heat conducting relation with said casing, a body having a relatively large mass to surface area ratio and high thermal conductivity secured to said member and shielded from direct heat radiation from said flame by said member, a second temperature responsive resistance mounted on said body in heat conducting relation therewith and adapted while flame is present in said combustion chamber to be maintained at a second temperature defining a temperature differential between said first and second temperatures; said casing, said member and said body operating to rapidly decrease said temperature differential upon extinction of said flame.

4. An apparatus for detecting the presence or absence of heat radiation comprising, a casing having an open end adapted to face the source of said heat radiation, a first temperature responsive resistance within said open end of the casing adapted to be exposed to direct heat radiation and heated to a first temperature by the presence of heat radiation; a member having high thermal conductivity secured in heat conducting relation with said casing; a body having a relatively large mass to surface area ratio and high thermal conductivity secured to said member and shielded from direct heat radiation by said member; a second temperature responsive resistance mounted on said body in heat conducting relation therewith and adapted while heat radiation is present to be maintained at a second temperature defining a temperature differential between said first and second temperatures; said casing, said member, and said body forming a heat conducting path to rapidly decrease said temperature differential when heat radiation is absent.

5. An apparatus for detecting the presence or absence of heat radiation comprising, a casing having an open end adapted to face the source of said heat radiation, a member having high thermal conductivity secured within said open end of the casing in heat conducting relation thereto; a first temperature responsive resistance mounted on said member in heat conducting relation therewith and adapted to be exposed to direct heat radiation, said first resistance being heated to a first temperature when heat radiation is present; a body having a relatively large mass to surface area ratio and high thermal conductivity secured to said member and shielded from direct heat radiation by said member; a second temperature responsive resistance mounted on said body in heat conducting relation therewith and adapted

while heat radiation is present to be maintained at a second temperature defining a temperature differential between said first and second temperatures, said casing, said member, and said body forming a heat conducting path operating to rapidly decrease said temperature differential when said heat radiation is absent.

6. An apparatus for detecting the presence or absence of heat radiation comprising, a casing having an open end adapted to face the source of said heat radiation, a member having high thermal conductivity secured within said open end of the casing in heat conducting relation thereto, a first resistor having a relatively high, negative thermal coefficient of resistance mounted on said member in heat conducting relation therewith and adapted to be exposed to direct heat radiation, said first resistor being heated to a first temperature when heat radiation is present, a body having a large mass to surface area ratio and high thermal conductivity secured to said member and shielded from direct heat radiation by said member; a second resistor having a relatively high, negative thermal coefficient of resistance mounted on said body in heat conducting relation therewith and adapted while heat radiation is present to be maintained at a second temperature defining a temperature differential between said first and second temperatures; said casing, said member and said body forming a heat conducting path operating to rapidly decrease said temperature differential when said heat radiation is absent.

7. An apparatus for detecting the presence or absence of heat radiation and adapted to control an electric discharge device through a thermally created unbalance in a resistance network, said apparatus comprising, a tubular casing having an open end adapted to face the source of said heat radiation, a member having a small mass to surface area ratio and high thermal conductivity mounted within said open end of the casing and secured in heat conducting relation thereto, a first temperature responsive resistance mounted on said member in heat conducting relation therewith and adapted to be exposed to direct heat radiation, said first resistance being heated to a first temperature when heat radiation is present, a body having a relatively large mass to surface area ratio and high thermal conductivity secured to said member and shielded from direct heat radiation by said member, a second temperature responsive resistance mounted on said body in heat conducting relation therewith and adapted while heat radiation is present to be maintained at a second temperature defining a temperature differential between said first and second temperatures, said casing, said member and said body forming a heat conducting path operating to rapidly decrease said temperature differential when said heat radiation is absent.
